PRESSURIZED GAS BURNER

Gordon H. Brown and Creston J. Bruce, St. Joseph, Mich., assignors to Whirlpool Corporation, a corporation of Delaware

Filed Oct. 2, 1961, Ser. No. 142,285

12 Claims. (Cl. 158—99)

This invention relates to a new design for a gas burner for use on a domestic gas range or cooking stove.

The design of the burner is directed to features that overcome some of the undesirable features inherent in many of the present-day range gas surface burners of the atmospheric type.

Present atmospheric gas surface burners require large amounts of secondary air to effect efficient as well as safe combustion. This large secondary air requirement makes it essential that the burner combustion area be above the range so that secondary air is readily available. However, when a utensil or pan is set on the burner grates, the space between the periphery of the pan and the range top sometimes is restricted to the extent that enough secondary air can not pass through this space to the combustion area directly below the pan to assure efficient and safe combustion under all conditions. Therefore, it is customary in domestic gas range design to provide a clearance between the gas burner and the range top as an additional source of secondary air from below the range top to assure efficient and safe combustion under all conditions. This second necessary space for secondary air flow is very undesirable when the inevitable spillage or "boiling over" from the cooking pan takes place since the spillage may flow through this space and onto the burner gas supply lines and controls below the range top creating a very difficult cleaning problem. This spillage can also plug some of the burner gas outlet ports.

In addition to the psychological disadvantages of an exposed open flame above the range top there are also other important disadvantages. Naturally, if care is not taken, it is possible to ignite articles of clothing and items such as hot pads when moving pans about on the range top. Also, the necessity of having the combustion area above the range top to assure the required quantity of atmospheric secondary air allows the burner flame to sometimes directly impinge on the cooking pan causing permanent charring or discoloration of the cooking pans or utensils over and above that caused by the hot gases.

Thus, the gas burner of this invention is designed to eliminate the above explained disadvantages inherent in present-day ranges using atmospheric gas surface burners. Specifically, the gas burner of this invention is designed to provide a combustion area that is completely below the range cook top so that the burner flame is not visible. This in addition to eliminating an exposed flame also eliminates the direct impingement of the flame against the cooking utensils and thus tends to eliminate the permanent damage to the utensils caused by direct flame contact.

Since the combustion area of the burner of this invention is below the range cook top, it is not exposed to the necessary quantities of atmospheric secondary air for efficient and safe combustion. To overcome this deficiency, the entire burner including the primary air intake venturi is enclosed below the cook top in a shell or casing provided with an opening through which the required quantity of secondary air is delivered to the combustion area at an air pressure slightly greater than atmospheric pressure. The combustion area of the burner of this invention is defined by the burner parts adjacent the gas manifold outlet ports, the burner parts adjacent the pressurized secondary air ports and by the utensil support or burner cover. The central open portion of the utensil support extends downwardly through the cook top

2

to a point below the combustion area that surrounds this downwardly extending support portion. A spillage collecting cup or pan is positioned in the burner beneath the central opening in the utensil support. Since an additional opening is not needed in the cook top to supply secondary air for combustion, all spillage must pass through the central opening in the utensil support and into the spillage collector cup. There is practically no possibility of spillage getting onto the burner parts thus, it is only necessary to remove the utensil support and spillage collector cup in case of spillage.

The slight pressure differential over atmospheric pressure of the incoming secondary air to the combustion area also provides a positive air flow that overcomes the natural air flow due to convection to drive the heat of combustion downwardly out of the combustion area around the bottom of the depressed central portion of the utensil support and upwardly through the central opening to contact and heat the cooking utensil.

20 The gas burner of this invention is also adapted to be converted to a simple atmospheric burner in case pressurized secondary air is not used. To do this it is only necessary to provide a different utensil support and to remove the spillage cup to allow secondary air at atmospheric pressure to flow through the area formerly closed by the spillage cup into the combustion area.

Other features and advantages of the invention will be apparent from the following description taken in connection with the accompanying drawing wherein the figure is a diametric vertical section of a gas burner embodying the invention.

In the exemplary embodiment of the invention as disclosed in the drawing, a gas burner generally designated 10 is shown to comprise a housing, or box, 11 having an upper wall or cook top 12 provided with a central opening 13. Air at a pressure somewhat above atmospheric pressure is delivered to within the housing 11 by means of a conventional fan 14 driven by conventional means such as an electric motor (not shown). Within 35 the housing 11 is mounted an annular insulating support 15 provided with a radially inwardly projecting annular edge portion 16 supporting an outwardly turned flange 17 of a sump or spillage pan 18 depending downwardly through an opening 19 in the bottom wall 20 of the housing or casing 11. A hollow annular burner ring 21 is supported on the planar upper surface 22 of the support 15 and is provided with a plurality of main outlet ports 23 opening through an upwardly widening frusto-conical surface 24. Combustible gas and primary air is supplied 40 to the annular chamber or manifold 25 within ring 21 through a duct 26 provided with a venturi portion 27 having an inlet 28 for providing primary air for mixture with the combustible gas in the venturi section prior to delivery through duct 26 to the burner ring. It should 45 be noted that the venturi portion 27 and primary air inlet 28 are positioned within the casing 11 and thus primary air enters the inlet 28 at the pressure above that of the ambient atmosphere around casing 11 and created within the casing 11 by the blower 14. A main gas line 29 extends through the bottom wall 20 of the casing 11 and connects with a modulating type gas flow control valve 29a to control the flow of gas to the outlet ports from the gas inlet line 28a. A pilot gas line is connected to the gas inlet line 28a before the valve 29a and extends 50 upwardly through the bottom wall 20 of the casing 11 so that the pilot line outlet portion 31 is adjacent the main outlet ports 23. This arrangement provides a standing pilot to ignite the gas flowing through the ports 23 as controlled by the valve 29a. If desired, other ignition 55 means could be used.

Extending upwardly from the upper surface 32 of the burner ring 21 is a frusto-conical, upwardly narrow-

ing wall member 33 provided with a plurality of circumferentially spaced secondary air apertures 34. Wall member 33 and burner ring 21 co-operatively define an outer boundary of a combustion chamber 35 wherein the gas delivered through ports 23 is burned, the combustion being supported by the primary air delivered through opening 28 to the venturi section 27, and secondary air delivered to the combustion chamber 35 through apertures 34.

The inner boundary of combustion chamber 35 is defined by a radially inner, downturned portion 36 of a ceramic cover or utensil support 37, extending downwardly radially inwardly of the insulating support 15. Thus, combustion chamber 35 comprises a downwardly opening annular chamber wherein the flames 38 produced by the burning combustible gas are effectively covered so that no live flame is exposed upwardly. The hot products of combustion, however, pass downwardly because of the pressure of the secondary air produced by the blower 14 from the combustion chamber 35 and then upwardly through the central circular opening 39 defined by cover portion 35 to heat a superposed element to be heated, such as a cooking utensil E. This pressurized air assures proper combustion, heat transfer, and air flow contra to that normally produced in natural convection.

A downwardly directed flange 40a of cover 37 is supported in resting engagement on the upper wall portion 12 of the housing 11 to support the cover 37. The cover is provided with a right cylindrical surface 41 engaging a wall member flange 40 of wall member 33 to retain the cover coaxially in the burner. As shown, the inner surface 42 of the cover preferably flares outwardly thereby facilitating the delivery of the hot products of combustion upwardly from the burner and providing a wide uniform distribution thereof effectively precluding the formation of hot spots on the bottom of utensil E. To facilitate the flow of the hot products of combustion under substantially the entire bottom surface 43 of the utensil, circumferentially spaced, radially extending support ribs 44 are molded integrally with the cover 37 to provide radial passages for the hot gases against the bottom 43 of the utensil E. It is also possible to make the cover 37 and ribs as separate parts. The cover and ribs have to be designed to provide a dispersed air flow at a controlled velocity of flow.

Thus, burner 10 provides an improved convective heating of the utensil or element to be heated. Upward exposure of the flame is effectively precluded, the heating of the utensil being effected by the hot products of combustion passing upwardly from the burner in a uniform even distribution against the utensil. Air for supporting combustion of the combustible gas in the combustion chamber is provided thereto at a positive pressure, assuring the necessary quantity of secondary air for high efficiency and safe operation. The cover 37 and sump pan 18 are readily removable for facilitated cleaning. Further, as the combustion chamber is effectively covered by the cover 37, spillage is directed away from the burner ports thereby effectively assuring a simple cleaning job in case of spillage and also practically eliminating the possibility of the burner being completely extinguished with the valve 29a remaining open.

Still another desirable feature of the burner 10 is the arrangement thereof for ready use as a generally conventional exposed flame atmospheric burner utilizing ambient, non-pressurized air as, for example during a power failure, when fan 14 becomes inoperative. Thus, the ready removal of cover 37 and replacing it with a new cover not having the depending portion 36 and the removal sump pan 18 converts the burner to such an exposed flame, atmospheric-air-utilizing burner.

While we have shown and described one embodiment of our invention, it is to be understood that it is capable of many modifications. Changes, therefore, in the construction of individual components and arrangement

may be made without departing from the spirit and scope of the invention as defined in the appended claims.

We claim:

1. A burner comprising: means defining a combustion chamber; means providing combustible gas and primary air at a positive pressure to said chamber; means providing secondary air at a positive pressure to said chamber for supporting combustion of said gas to provide a flame therein; cover means fully overlying said chamber for effectively fully precluding upward exposure of the flame in normal operation of the burner, said cover means defining a passage for passing hot products of combustion upwardly to heat a superposed element; and insulating means for directing the products of combustion from said chamber to said passage with effectively maintained thermal energy content.

2. The burner of claim 1 wherein said cover partially laterally defines said chamber.

3. The burner of claim 1 wherein said cover is readily removable.

4. The burner of claim 1 wherein said combustion chamber opens downwardly.

5. A burner comprising: means defining an annular combustion chamber; means providing combustible gas and primary combustion-supporting air to said chamber to provide a flame therein; cover means overlying said chamber for effectively fully precluding upward exposure of the flame in normal operation of the burner, said cover means defining an axial passage for passing hot products of combustion upwardly from said chamber to heat a superposed element; and sump means coaxially subjacent said axial passage for collecting spillage and the like.

6. A burner comprising: means defining an annular combustion chamber; means providing combustible gas and primary combustion-supporting air to said chamber to provide a flame therein; means providing secondary air to said chamber for additionally supporting combustion of said combustible gas therein; cover means overlying said chamber for effectively fully precluding upward exposure of the flame in normal operation of the burner, said cover means defining an axial passage for passing hot products of combustion upwardly from said chamber to heat a superposed element; and sump means coaxially subjacent said axial passage for collecting spillage and the like.

7. The burner of claim 5 wherein said sump means and said cover means are axially upwardly removably carried by said chamber defining means.

8. The burner of claim 5 wherein said sump means is disposed substantially below the level of said combustion chamber.

9. A burner comprising: wall means defining a combustion chamber, a first opening in said wall means for delivering combustible gas and primary air mixture into said chamber to provide a flame therein, a second opening in said wall means for delivering secondary air into said chamber for supporting effectively complete combustion of said gas in said chamber, said first and second openings opening into said chamber perpendicularly to each other and said second opening being disposed above said first opening; and cover means fully overlying said chamber for effectively fully precluding upward exposure of the flame in normal operation of the burner, said cover means defining a passage for passing hot products of combustion upwardly from said chamber to heat a superposed element.

10. Burner apparatus comprising: means defining a closed space; a burner in said space; means defining a passage through said space for delivering combustible fuel to said burner, said passage means having an opening to said space; means defining a combustion chamber having an opening to said space, said burner having an opening to said combustion chamber opening substantially perpendicularly and adjacent said chamber open-

ing; means for delivering air under pressure to said space for passing through said opening in the passage means to comprise primary air mixed with the combustible fuel in said passage means and for passing through said opening in said chamber means to comprise secondary air in said chamber for impinging substantially perpendicularly against a flame emanating from said burner opening and thereby providing improved effectively complete combustion therein; cover means fully overlying said chamber for effectively fully precluding upward exposure of the flame in normal operation of the burner, said cover means defining a passage for passing hot products of combustion upwardly to heat a superposed element; and insulating means for conducting products of combustion from said chamber to exteriorly of the space defining means.

11. A range surface burner comprising: wall means defining an enclosed cavity and having first and second apertures; a hollow, upwardly flared cover member seated in said first aperture and depending into said cavity; a burner ring positioned within said cavity and encompassing the cover member depending into said cavity; a perforate wall means encompassing the cover member depending into said cavity and cooperating with said cover member and said burner ring to define a combustion chamber therewith; means including a venturi communicating with said burner ring and supplying said burner ring with a combustible air-gas mixture; and air translation means positioned adjacent said second aperture for supplying pressurized secondary air to said com-

5 bustion chamber and to said venturi to promote complete combustion of said air-gas mixture within said combustion chamber prior to exhaustion of effluent hot gases upwardly through said hollow cover member, said cover member effectively fully precluding upward exposure of the flame in normal operation of the burner.

10 12. A burner comprising: means defining a combustion chamber; means providing combustible gas and primary air at a positive pressure to said chamber; means providing secondary air at a positive pressure to said chamber for supporting combustion of said gas to provide a flame therein; and cover means fully overlying said chamber for effectively fully precluding upward exposure of the flame in normal operation of the burner, said cover means defining a passage for passing hot products of combustion upwardly to heat a superposed element.
